Katsuji M. Fujima

UNITED STATES PATENT OFFICE.

SEIZI TADAKUMA, OF LOS ANGELES, CALIFORNIA.

SNAP-FASTENER FOR SHOES.

1,343,942.

Specification of Letters Patent. Patented June 22, 1920.

Application filed February 10, 1920. Serial No. 357,643.

To all whom it may concern:

Be it known that I, SEIZI TADAKUMA, a subject of the Emperor of Japan, residing at Los Angeles, in the county of Los Angeles and State of California, have invented a new and useful Snap-Fastener for Shoes, of which the following is a specification.

This invention has relation to an improved means for securing the shoe to the foot of the wearer, and its objects are to provide a securing means which may be readily applied to the shoe, which may be quickly secured in the clamping position, and which may be changed in position to accommodate the shoe to the foot of the wearer, without mutilating and disfiguring the leather fabric forming the upper part of the shoe.

A further object of this invention is to provide a shoe-fastener which is durable, inexpensive to manufacture, well adapted to withstand rough usage, and which is attractive in appearance, and which may be readily applied to the shoe by any person unskilled in the art.

While the device as herein described is well adapted to serve the purposes for which it is intended, it is to be understood that minor changes in form and details of construction may be resorted to without departing from the invention or sacrificing any of its advantages.

Upon the annexed drawings, Figure 1 is a perspective view of a shoe provided with my improved fasteners. Fig. 2 is a perspective view of the inner shoe flap fastener. Fig. 3 shows a fragment of leather with the fastener attached thereto. Fig. 4 is a perspective view of a hook fastener adapted for the outer shoe flap. Fig. 5 is a fragmentary detail view showing the hook fastener attached to the leather fabric. Fig. 6 is a bottom plan view of the hook fastener shield. Fig. 7 is a top plan view of the same. Fig. 8 is a perspective view of a hook formed from a single line of wire. Fig. 9 is a perspective detail view of the hook fastener formed and stamped from sheet metal. Fig. 10 is a cross-section of the hook loop. Fig. 11 is a sectional view through a fragment of the shoe fabric, showing the fastener attached and provided with a reinforcement beneath the shield.

Referring to the drawings, the fastener consists of a loop member 11 adapted to be

secured to the inner flap 12 of a shoe; the fastener consisting of a loop bar 13 connecting the staple members 14, and angularly disposed therewith; the members 14 having prongs 15 adapted to pierce the leather fabric of the shoe and clench on the under side of the inner flap. On the outer shoe flap 16, I provide a corresponding series of hook members 17, relatively broad and flat to engage with bars 13. Members 17 are provided with angularly projecting prongs 18, adapted to pierce the shoe fabric and extend through apertures 19, in bottom plates 20, of shield members 21. Members 21 have a corrugated surface 22, of ornamental appearance and facilitating manipulation of the shoe flap to place the hook and loop fasteners in operative engagement to secure the shoe. A reinforcing member 23, serves to turn the prongs 18 to clench upon the bottom plate.

In affixing these fasteners, the hook members are placed on the inner side of the shoe flap, with prongs 18 piercing the shoe fabric. The shields are applied upon the opposite side of the shoe fabric and pressed into engagement with the projecting prongs 18, which turns the prongs to clench upon the inner shield plates. In changing the fasteners so that the shoe will fit the foot of the wearer, the shield members may remain in their original position, and the inner securing members be changed. The loop members may be removed by loosening the clenched prongs which project through the inner flap, and the loop members may then be applied again. As the loop member is formed throughout in a very small cross-section, the perforations left by the removal of the loop members will be very small and such as will not detract from the neat appearance of the shoe.

In use, the hook fastener and loop fasteners are designed to hold the shoe flaps relatively close together, and the shoe is quickly secured by engaging the fasteners with one another.

What is claimed is:

1. A shoe securing member consisting of a hook disposed on the underside of a shoe flap, prongs on the hook piercing the flap, a shield on the opposite side of the flap having a perforated bottom, said prongs projecting through the perforations and being

clenched to said shield bottom, and corresponding loop fasteners on the opposite flap of the shoe.

2. A shoe securing member consisting of 5 a hook, securing prongs projecting therefrom and piercing the leather fabric, a shield on the outer side of the flap and incasing the prongs, said prongs being clenched to the shield, and a loop fastener disposed on the opposite flap of the shoe and adapted to engage with the hook.

3. The combination with a shoe having outer and inner contiguously disposed securing flaps, of loop bars clenched to the inner flap, and corresponding hook members secured to the outer flap, and shield members disposed on the outer flap and in engagement with the hook members. 15

In testimony whereof, I hereunto affix my signature, this 31st day of January, 1920. 20

SEIZI TADAKUMA.
